UNITED STATES PATENT OFFICE

CHARLES A. GEARING, OF BELLWOOD, ILLINOIS

DESIGN FOR A FLAG

Application filed September 29, 1932. Serial No. 45,165. Term of patent 14 years.

To all whom it may concern:

Be it known that I, CHARLES A. GEARING, a citizen of the United States, residing at Bellwood, in the county of Cook and State of Illinois, have invented a new, original, and ornamental Design for a Flag, of which the following is a specification, reference being had to the accompanying drawing, forming part thereof.

The figure is a perspective view of a flag.

I claim:

The ornamental design for a flag, as shown.

CHAS. A. GEARING.
